UNITED STATES PATENT OFFICE.

GEORGE LAWSON ROBERTSON, OF PHILADELPHIA, PENNSYLVANIA, ASSIGNOR OF
ONE-HALF TO CHARLES MITCHELL, OF PHILADELPHIA, PENNSYLVANIA.

PNEUMATIC HAMMER.

1,078,384.

Specification of Letters Patent. Patented Nov. 11, 1913.

Application filed July 11, 1913. Serial No. 778,489.

To all whom it may concern:

Be it known that I, GEORGE LAWSON ROBERTSON, a citizen of the United States, residing at Philadelphia, in the county of 5 Philadelphia and State of Pennsylvania, have invented certain new and useful Improvements in Pneumatic Hammers, of which the following is a specification.

My invention relates to improvements in 10 pneumatic hammers, the object of the invention being to provide an improved valve mechanism controlling the reciprocation of the plunger.

A further object is to provide an improved arrangement of ports and passages 15 and an improved construction of valve which automatically shifts its position to control the flow of fluid and insure a rapid reciprocation of the plunger.

With these and other objects in view, the 20 invention consists in certain novel features of construction and combinations and arrangements of parts as will be more fully hereinafter described and pointed out in the 25 claims.

In the accompanying drawings: Figure 1 is a view in longitudinal section illustrating 30 my improvements. Fig. 2 is a view in cross section on the line 2—2 of Fig. 1. Fig. 3 is a view in cross section on the line 3—3 of Fig. 1. Fig. 4 is a perspective view of the 35 valve. Fig. 5 is a fragmentary view in section on the line 5—5 of Fig. 2, and Fig. 6 is a fragmentary view in longitudinal section showing the valve in its forward or shifted position.

1 represents the barrel of a pneumatic hammer having a longitudinal bore 2 in which a plunger 3 snugly fits and is adapted 40 to reciprocate. The barrel 1 at its rear end is enlarged in diameter and made hollow forming a cylindrical extension 4 in which a valve box 5 is mounted. The valve box 5 is held against rotary movement in the 45 barrel by means of pins 6, and at its rear end has an annular flange 7 fitting against the end of the barrel.

The hammer handle 8 is provided with a cylindrical cap 9, internally screw-threaded 50 and engaging screw-threads on the cylindrical extension 4 of the barrel.

An internal annular shoulder 10 is provided in the cap which bears against the flange 7 securely binding this flange between

said shoulder and the end of the cylindrical 55 extension 4, so that longitudinal movement of the valve box is effectually prevented.

The cylindrical extension 4 has an annular series of ratchet teeth 11 in which a spring-pressed pin 12 engages to hold the 60 parts against accidental movement.

In the box 5, my improved valve 13 is mounted to reciprocate and has a longitudinal bore alining with the bore 2 of the barrel, and of the same diameter so that the 65 plunger fits snugly within the valve and reciprocates therethrough.

The valve 13 is open at both ends, its movement in a forward direction being limited by a shoulder 14 in box 5, and the movement in the rearward direction limited by 70 an internal annular flange 58.

The cylindrical central opening or bore of box 5 at its rear end is closed by a cylindrical block 16 forming an integral part of 75 my improved movable box head 17 which is cylindrical in form, and has a leather disk cup 18 secured to a central lug 19 thereon by means of a washer 20, and a pin 21, and this cup 18 with the head 17 is adapted 80 to reciprocate in a cylindrical casing 22. This casing 22 fits snugly within the fluid inlet chamber 23 at the rear end of the hammer provided within the cap 9, so that the head 17 is always open to communication 85 with the live fluid pressure entering through inlet passage 24, and is normally pressed forwardly as indicated.

The forward end of the block 16 forming an integral part of head 17 is reduced in diameter and snugly fits within the flange 58, and the rear end of valve 13, so as to form a cushioning head for an air pocket at the rear end of the valve. This block 16 has a central chamber 25 which communicates 95 by radial ports 26 with an annular groove 27 around the block. This groove 27 is normally out of alinement with radial ports 28 between the end of casing 22 and valve box 5. These radial ports which may constitute 100 a continuous chamber, communicate with longitudinal grooves 29 in the outer surface of casing 22, and I would have it understood that when I use this term "radial ports" for the passage 28, that the term is 105 used in its broadest sense.

Casing 22 is secured by screws 30 to the box 5, so that it is held against movement.

The live fluid entering passage 24 when the parts are in the position shown in Fig. 1, passes through the grooves 29, radial ports 28, and relatively large longitudinal ducts 31 in box 5, and through openings 32 in valve 13, so as to drive the plunger forwardly.

The rearward movement of the plunger will cause an air pocket or cushion between the plunger and the head, and the head will be moved rearwardly until the ports 26 register with the ports 28. Instantly, the live fluid will flow through the ports 26 and chamber 25, and give the plunger its initial forward movement. The action therefore of the head operates to cushion the plunger and admit fluid back of the plunger to accelerate its forward movement. The head will be instantly returned to its normal position by the pressure of live fluid behind the same, but the momentary rearward movement further compresses the fluid and to that extent, increases the power thereof to drive the plunger forwardly.

My improved hammer is provided at its forward end with a removable rivet set 33 and a guard 34, and it is to be understood that the plunger and its reciprocation strikes the set as is customary.

My improved arrangement of passages and ports in the box and barrel are as follows: The longitudinal inlet ports 31 have two outlets 35 and 36, the former discharging directly into an annular groove 37 around valve 13 when the valve is in its rearward position. The ports 32 above referred to communicate with this groove 37, so that the live fluid flows directly into the valve and drives the plunger forwardly. The fluid in front of the plunger exhausts through passages 38 into a circumferential groove 39, thence through radial ports 40 into longitudinal passages 15 which are exhaust passages and discharge at their forward ends into the atmosphere.

When the piston moves forwardly and its rear end uncovers ports 41 communicating with longitudinal passages 42, the live fluid will flow through the longitudinal passages 42 to reverse the valve 13 as will be herein-after explained.

The valve 13 is provided with an annular enlargement 43 having an annular flange 44 at one end, and an annular groove 45 between its ends. This valve 13 at its rear cylindrical portion is provided with the annular grooves 37 and 39 above referred to.

The annular flange 44 at one end of the annular enlargement 43 provides a relatively large pressure surface 46 on the rear end of the enlargement and also provides a relatively small pressure surface 47 on the forward side of the flange. The forward end of the cylindrical enlargement 43 forms an annular shoulder 48 which moves toward 65 and away from an internal shoulder 49 in

the valve box forming an annular air space 50 which is connected at all times by radial ports 51 with the passages 15, so that this air space 48 is in constant communication with the atmosphere and prevents partial vacuum or compression, allowing the valve to freely reciprocate without opposition from these surfaces.

The relatively large pressure surface 46 moves toward and away from an annular shoulder 52 in the valve box, and the space between said pressure surface 46 and the shoulder 52 communicates with the longitudinal passages 42 above referred to.

The relatively small pressure surface 47 is always in communication with the live fluid through the medium of longitudinal passages 53 in the valve box which connect the passages 31 with the space in front of the pressure surface 47.

The annular groove 45 in valve 13 is adapted when the valve is moved forwardly to connect longitudinal passages 54 with radial passages 55, the latter communicating with the exhaust passages 15. The passages 54 are relatively short, and operate as exhaust passages when the plunger is on its rearward stroke.

The operation is as follows: In Fig. 1 the plunger is moving forwardly and the live fluid is entering through passages 31, ports 35, and openings 32, driving the plunger forwardly. The fluid in advance of the plunger is forced through the passages 38, groove 39, ports 40, and passages 15 to the atmosphere. When the plunger uncovers ports 41, the live fluid will flow through passages 42 and exert pressure upon the pressure surface 46 to drive the valve to its forward position. Immediately the live fluid will pass through passages 31 and ports 36, thence through groove 39 and longitudinal passages 57 to the forward end of the barrel to drive the plunger rearwardly. The fluid in front of the plunger will be forced through passages 54, groove 45, radial ports 55, and exhaust ports 15. A portion of this air in front of the plunger will also be forced out through openings 32, groove 37, and radial ports 56 into passages 15. When the forward end of the plunger on the rearward stroke of the latter uncovers passages 54, a portion of the live fluid will escape to the atmosphere, relieving the pressure on surface 46, allowing the pressure of live fluid on surface 47 to shift the valve to its rearward position.

As the plunger completes its rearward stroke, it will be cushioned by the action of the head 7 as above explained, and will immediately begin its forward stroke.

Various slight changes might be made in the general form and arrangement of parts described without departing from my invention, and hence I do not limit myself to the precise details set forth, but consider myself 130

at liberty to make such changes and alterations as fairly fall within the spirit and scope of the appended claims.

Having thus described my invention, what
5 I claim as new and desire to secure by Let-
ters Patent is:

1. In a pneumatic hammer, the combination with a barrel, and a reciprocating plunger in the barrel, of a valve box secured to the barrel, a reciprocating valve in the box through which the plunger moves, said valve and box constructed to form an annular air space adjacent the forward end of the valve, and said air space always maintained in communication with the outside air, said valve having two annular opposed pressure surfaces of different areas, and fluid passages in the barrel and box controlled by the plunger for regulating the pressure against one of the surfaces to compel the valve to reverse as the plunger nears the ends of its stroke, substantially as described. 75

10 15 20

faces of different areas, fluid passages in the barrel and box controlled by the plunger for regulating the pressure against one of the surfaces to compel the valve to reverse as the plunger nears the ends of its stroke, and said valve having ports therein registering with the passages in the box, and controlling the flow of fluid to operate the plunger, the smaller of said surfaces always in communication with the live fluid, and the larger of said surfaces in communication with the live fluid during a portion only of the stroke of the plunger, substantially as described. 80

2. In a pneumatic hammer, the combination with a barrel, and a reciprocating plunger in the barrel, of a valve box secured to the barrel, a reciprocating valve in the box through which the plunger moves, said valve and box constructed to form an annular air space adjacent the forward end of the valve, and said air space always maintained in communication with the outside air, said valve having two annular opposed pressure surfaces of different areas, and fluid passages in the barrel and box controlled by the plunger for regulating the pressure against one of the surfaces to compel the valve to reverse as the plunger nears the ends of its stroke, substantially as described. 85

20

2. In a pneumatic hammer, the combination with a barrel, and a reciprocating plunger in the barrel, of a valve box secured to the barrel, a reciprocating valve in the box through which the plunger moves, said valve and box constructed to form an annular air space adjacent the forward end of the valve, and said air space always maintained in communication with the outside air, said valve having two annular opposed pressure surfaces of different areas, and fluid passages in the barrel and box controlled by the plunger for regulating the pressure against one of the surfaces to compel the valve to reverse as the plunger nears the ends of its stroke, and said valve having ports therein registering with the passages in the box, and controlling the flow of fluid to operate the plunger, substantially as described.

6: In a pneumatic hammer, the combination with a barrel, and a reciprocating plunger in the barrel, of a valve box secured to the barrel, a reciprocating valve in the box through which the plunger moves, said valve and box constructed to form an annular air space adjacent the forward end of the valve, and said air space always maintained in communication with the outside air, said valve having two annular opposed pressure surfaces of different areas, fluid passages in the barrel and box controlled by the plunger for regulating the pressure against one of the surfaces to compel the valve to reverse as the plunger nears the ends of its stroke, said valve having ports therein registering with the passages in the box, and controlling the flow of fluid to operate the plunger, said opposed surfaces formed by an annular flange at one end of an annular enlargement on the valve, the other end of said annular enlargement always in communication with the atmosphere, substantially as described. 105 110 115 120 125

7. In a pneumatic hammer, the combination with a barrel, and a reciprocating plun- 130

- ger in the barrel, of a valve box secured to the barrel, a reciprocating valve in the box through which the plunger moves, said valve and box constructed to form an annular air space adjacent the forward end of the valve, and said air space always maintained in communication with the outside air, said valve having two annular opposed pressure surfaces of different areas, fluid passages in the barrel and box controlled by the plunger for regulating the pressure against one of the surfaces to compel the valve to reverse as the plunger nears the ends of its stroke, the smaller of said surfaces always in communication with the live fluid, the larger of said surfaces in communication with the live fluid during a portion only of the stroke of the plunger, said opposed surfaces formed by an annular flange at one end of an annular enlargement on the valve, the other end of said annular enlargement always in communication with the atmosphere, substantially as described.
8. In a pneumatic hammer, the combination with a barrel, and a reciprocating plunger in the barrel, of a valve box secured to the barrel, a reciprocating valve in the box through which the plunger moves, said valve and box constructed to form an annular air space adjacent the forward end of the valve, and said air space always maintained in communication with the outside air, said valve having two annular opposed pressure surfaces of different areas, fluid passages in the barrel and box controlled by the plunger for regulating the pressure against one of the surfaces to compel the valve to reverse as the plunger nears the ends of its stroke, said valve having ports therein registering with the passages in the box, and controlling the flow of fluid to operate the plunger, the smaller of said surfaces always in communication with the live fluid, and the larger of said surfaces in communication with the live fluid during a portion only of the stroke of the plunger, said opposed surfaces formed by an annular flange at one end of an annular enlargement on the valve, the other end of said annular enlargement always in communication with the atmosphere, substantially as described.
9. In a pneumatic hammer, the combination with a barrel, and a reciprocating plunger in the barrel, of a valve box secured in the barrel, a reciprocating valve in said box through which the plunger moves, said valve and box constructed to form an annular air space adjacent the forward end of the valve, and said air space always maintained in communication with the outside air, said valve having two annular opposed pressure surfaces of different areas against which fluid is always directed tending to move the valve in both directions, and said barrel and box having fluid passages therein controlled by the plunger, whereby the pressure against one of said opposed pressure surfaces is regulated to compel the valve to move from one operative position to another, substantially as described.
10. In a pneumatic hammer, the combination with a barrel, and a reciprocating plunger in the barrel, of a valve box secured in the barrel, a reciprocating valve in said box, said valve having a cylindrical bore through which the plunger moves, and having two pressure surfaces adjacent its rear end, one smaller than the other, said valve having an annular surface opposing an annular surface in the box, said last-mentioned surfaces forming an air space maintained always in communication with the outside air, and said barrel and box having fluid passages therein controlled by the plunger, whereby the pressure against the larger of said pressure surfaces is regulated to compel the valve to move from one position to another, substantially as described.

In testimony whereof I have signed my name to this specification in the presence of two subscribing witnesses.
